UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

FEED-CONTROL MECHANISM.

Application filed January 19, 1920. Serial No. 352,540. Renewed October 14, 1922. Serial No. 594,655.

My invention relates to feed control mechanism.

Its object is to provide an improved feed control mechanism, and more particularly an improved feed control mechanism adapted to regulate the rate of feed of what is known as a stoping drill. A further object of my invention is to provide an improved feed controlling mechanism in which the parts are simple and of great strength.

In the accompanying drawings I have shown, for purposes of illustration, one form which my invention may assume in practice.

In these drawings,—

Fig. 1 is a plan view of a stoper provided with a feed control mechanism embodying the illustrative form of my invention.

Fig. 2 is an enlarged view of the feed cylinder shown in Fig. 1 with certain parts shown on the section line 2—2, and other parts in elevation.

Figs. 3 and 4 are, respectively, transverse sections on lines 3—3 and 4—4 of Fig. 2.

I have shown for purposes of illustration a stoper indicated generally by 1 in which a percussive motor 2 is adapted to actuate a drill steel 3 and to be fed toward or from the work by means of a feed cylinder indicated generally by 4, the operation of the motor and the supply of air to the feed cylinder being regulated in a well-known manner by a throttle valve 5. The feed cylinder 4 is secured, as shown in Fig. 2, to the rear end of, and coaxial with, the percussive motor 2. The feed cylinder comprises a cylinder member 6 in which there is reciprocably mounted a piston 7 provided with a piston rod 8 which has at its outer end a point 9 adapted to engage a supporting surface during operation of the tool.

As it is sometimes difficult, for example, when starting a hole, to regulate the feed in the desired manner by means of the manual valve 5 alone, I have provided, to cooperate with the cylinder 6 and piston rod 8, a feed controlling mechanism indicated generally by 11. Rigidly secured to the end of the piston rod 8 and adjacent the point 9, there is arranged a cross arm 12 which receives at opposite ends a pair of side rods 13 which are connected at their opposite ends to a slideable member 14 surrounding the exterior of the cylinder 6. The engagement of the rods 13 with the members 12 and 14 maintains them in parallel relation to the feed cylinder.

Cooperating with the rods 13 and fixedly secured, as by rivets 15, relative to the rear end of the feed cylinder is a clamping mechanism generally indicated by 17. The clamping mechanism consists generally of two semicircular members 18 and 19 pivotally connected at one end, as at 20, by means of one of the side rods 13 and provided at their other ends, i. e., at their free ends, with oppositely disposed sockets 21. These sockets conform in shape to the side rods and are lined with suitable brake material 22, as shown in Fig. 3. A bolt 24 is arranged between the outer ends of the clamp members 18 and 19 and a nut 25 provided with a handle 26 is arranged to cooperate with the bolt 24 in the application and releasing of the clamp. I have here shown the bolt 24 with left hand thread.

From the foregoing description the operation of my improved mechanism will be readily apparent. Assume the piston 7 to be in the position indicated in Figs. 1 and 2 and that air is admitted to the forward end of the feed cylinder to cause the drill to feed toward the work. Let it also be assumed that the handle 26 is given a right hand turn sufficient to release the frictional engagement of the clamp members 19 and 20 with the right hand side rod 13 in Fig. 3. The rate of feed will then be controlled only by the air supplied under control of the valve 5. Should it be desired to retard the rate of feed or to stop the feed entirely, all that is necessary is to give a left hand rotation to the handle 26 which will cause the nut 25 to screw down upon the bolt 24 and swing arm 19 of the clamp about the pivot 13 and cause the brake lining 22 to be tightly pressed upon the side rod 13. It will be obvious that the rate of feed may be varied as desired in accordance with the degree of force exerted by the bolt 24 and nut 25 in pressing the brake lining against the side rod 13.

It will be evident that I have provided a very simple retarding device with a minimum number of parts and one in which bending strains will be entirely eliminated. It will further be obvious that by the nature of the pivotal connection 20 I have caused the application of a braking force on both side rods, although this is not true in equal degree on both sides. When the bolt 24 is placed under tension, the arm 19 will tend to pivot on the right hand side rod 13 and

frictionally engage at its pivot point the left hand side rod 13. Suitable means, e. g., a flat, prevents turning of the bolt 24.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a feed controlling mechanism, a stationary member engageable with an extraneous abutment, a member movable relative thereto during feeding and by which the member to be fed is carried, normally immovable means secured to said stationary member and arranged parallel to said movable member, and controlling means carried by said movable member and frictionally engageable with said first mentioned means to control the rate of feed.
2. In a feed controlling mechanism, a stationary member engageable with an extraneous abutment, a member movable relative thereto during feeding and by which the member to be fed is carried, a normally immovable member secured to said stationary member, and controlling means secured to said movable member and frictionally engageable with said third mentioned member to control the rate of feed.
3. In a feed controlling mechanism, a stationary member engageable with a mine surface, a movable member, a clamp secured to said movable member, a stationary bar engaged by said clamp and attached to said stationary member, and means for adjusting said clamp.
4. In a feed controlling mechanism, a stationary member provided with an abutment engaging point, a movable member coaxial therewith, a clamp secured to said movable member, a stationary side rod engaged by said clamp and attached to said stationary member, and means for adjusting said clamp.
5. In a feeding mechanism, a cylinder, a piston, a side rod connected to one of said members, and a clamp rigidly mounted with respect to the other of said members and adapted to frictionally engage said side rod.
6. In a feeding mechanism, a cylinder, a piston therein, a pair of side rods connected to one of said members, and a clamp stationary with respect to the other of said members and adapted to frictionally engage both of said side rods.
7. In a feed controlling mechanism, a stationary member, a cross member secured thereto, a movable member, a pair of side rods extending from said cross member parallel to the path of said movable member,

and a clamp fixed to said movable member cooperating with said side rods to frictionally engage one of them.

8. In a feed controlling mechanism, a stationary member, a cross member secured thereto, a movable member, a pair of side rods extending from said cross member parallel to the direction of motion of said movable member, and means cooperating with said side rods to frictionally engage both of them.

9. In a feed controlling mechanism, a stationary member, a pair of rods parallel to said stationary member and secured thereto, a movable member, a pair of clamp arms one of which is secured to said movable member and the other of which is frictionally engageable with one of said side rods.

10. In a feed controlling mechanism, a stationary member, a pair of rods parallel to said stationary member and secured thereto, a movable member, and a pair of clamp arms one of which is secured to said movable member and both of which are frictionally engageable with one of said side rods.

11. In a feed controlling mechanism, a pair of telescoping members, a pair of side rods secured in parallel relation therewith to one of said members and guided at their other ends by the other of said members, a clamping member surrounding one of said side rods and fixedly secured to said second mentioned telescoping member, a clamping member pivoted to said last mentioned side rod, and means to cause said clamping members to frictionally engage one of said side rods.

12. In a feed controlling mechanism, a pair of telescoping members, a pair of side rods secured in parallel relation to one of said members and guided at their other ends by the other of said members, a clamping member surrounding one of said side rods and fixedly secured to said second mentioned telescoping member, a clamping member pivoted to said last mentioned side rod, and means to cause said last mentioned clamping member to frictionally engage both of said side rods.

13. In a feed controlling mechanism, a pair of telescoping members, a pair of side rods secured in parallel relation to one of said members and guided at their other ends by the other of said members, a clamping member surrounding one of said side rods and fixedly secured to said second mentioned telescoping member, a clamping member pivoted to said last mentioned side rod, and means including a bolt connecting the free ends of said clamping members and a nut under manual control cooperating therewith to cause said clamping members to frictionally engage said side rods.

14. In a feed controlling mechanism, a pair of relatively reciprocable feeding mem-

bers one of which is engageable with a mine surface during feeding, means including side rods secured to one of said members and extending parallel to said line of reciprocation, and clamping means carried by the other of said members and adapted to engage said first mentioned means to control the rate of relative movement between said pair of members.

15. In a feed controlling mechanism, a pair of relatively reciprocable coaxial members one of which is engageable with a mine surface and the other of which is connected to a drilling tool, and means for regulating their relative movements during feeding including friction clamping means carried by one of said members, a member extending longitudinally of said members between which and the member which carries the friction clamping means relative movement occurs during feeding, and means whereby the application of pressure by said friction clamping means to said third mentioned member retards the relative movement between said pair of members.

16. In a feed controlling mechanism for drilling tools, a pair of relatively reciprocable coaxial members one of which is connected to a drilling tool and the other of which constitutes a fixed member engageable with a mine surface relative to which the first mentioned member and the tool move on feeding, a member extending longitudinally of said members between which and said first mentioned member relative movement occurs during feeding, and friction means secured to said first mentioned member and operative when applied and released to vary the force necessary to cause movement between said third mentioned member and said first mentioned member whereby relative movement between said first and second mentioned members may be controlled.

17. In a feed controlling mechanism, a pair of relatively reciprocable coaxial members one of which is provided with an abutment engaging point, means comprising side rods attached to one of said members and extending parallel to the said line of reciprocation, and clamping means carried by and movable with the other of said members and adapted to engage said side rods to retard relative movement between said pair of members.

18. In a feed controlling mechanism, a feeding device including a pair of relatively reciprocable coaxial members one of which is provided with an abutment engaging point, and means for regulating their relative movements during feeding including friction clamping means carried by one of said members, a member between which and one of said pair of members positive relative movement occurs during feeding, and means

whereby the application of pressure by said friction clamping means to said third mentioned member retards relative movement between said pair of members.

19. In a feed controlling mechanism for drilling tools, a pair of relatively reciprocable coaxial members one of which is connected to a drilling tool and the other of which constitutes a fixed member provided with an abutment engaging point relative to which the first member and the tool move on feeding, a member adapted to be movable with respect to said first mentioned member during feeding, and friction means secured to said first mentioned member and operative when applied and released to vary the force necessary to cause movement of said third mentioned member whereby relative movement between said first and second mentioned members may be controlled.

20. In a rock drilling mechanism, a drilling motor, feeding mechanism therefor comprising a feed cylinder element secured to said motor and a feed piston element reciprocably mounted therein and adapted to engage a stationary abutment during feeding, and controlling means therefor including a friction clamping means carried by said cylinder, a member between which and one of said elements relative movement occurs on relative reciprocation between said cylinder and piston elements, and means for causing said friction clamping means to frictionally engage said member whereby the rate of such relative reciprocation between said elements is controlled.

21. In a rock drilling mechanism, a drilling motor, feeding mechanism therefor comprising a feed cylinder element secured to said motor in alignment therewith, a normally stationary feed piston element reciprocably mounted therein provided with an abutment engaging point, and controlling means therefor including a friction clamping means carried by said cylinder element, a member between which and one of said pair of elements relative movement occurs on relative reciprocation between said elements, and means for causing said friction clamping means to govern the relative movement between said member and one of said elements whereby the rate of such relative reciprocation between said elements is controlled.

22. The combination with a pneumatic tool and pneumatic feeding means therefor comprising a cylinder and a piston rod, of feed varying means comprising a rod attached to said piston rod and means frictionally engaging said rod and secured to said cylinder.

23. In combination with a pneumatic tool and pneumatic feeding means therefor comprising a relatively movable feed cylinder and piston rod, a crosshead secured to said

piston rod, a member having sliding connection with said cylinder, rods connecting said crosshead and said member, and means carried by said cylinder and cooperating with said rods for controlling the movement between said cylinder and piston rod.

24. The combination with a pneumatic tool and pneumatic feeding means therefor comprising a relatively movable cylinder and a piston rod, of feed varying means including parallel rods secured to said piston rod, a member having sliding connection with said cylinder and attached to said rods, and means carried by said cylinder for controlling the relative movement therebetween.

25. In a feed controlling mechanism, a pair of relatively movable elements, a pair of rods carried by one of said elements, a clamp pivotally connected to one of said 20 rods and frictionally engageable with the other, and means to adjust said clamp to control the movement of said movable member.

26. In a feed controlling mechanism, concentric stationary and movable elements the former being disposed within the latter, a crosshead secured to said inner stationary element, a member having sliding connection with said outer movable element, par-

allel rods connecting said crosshead and 30 said last mentioned member, means carried by said movable element and including an element pivotally mounted on one of said rods and frictionally engageable with another, and means to adjust said friction 35 means.

27. In a feed controlling mechanism, a feeding cylinder, a stationary feed piston rod disposed coaxially therein, a crosshead secured to said piston rod, a member surrounding said cylinder and having sliding connection therewith, rods connecting said crosshead and said member, means secured to said cylinder and including an element pivotally mounted on one of said rods and 40 frictionally engageable with another, and means to adjust said friction means.

28. In a feed controlling mechanism, a pair of relatively reciprocable feeding members, a third member secured to one of said members and between which and one of said feeding members relative movement occurs during feeding, and a friction device secured to one of said feeding members and 50 frictionally engageable with said third member to govern the rate of feed.

In testimony whereof I affix my signature.
ELMER G. GARTIN.
